UNITED STATES PATENT OFFICE

PAUL SUSOL, OF BRACKENRIDGE, PENNSYLVANIA

BOTTLE SEAL

Application filed December 31, 1928. Serial No. 329,476.

This invention relates to certain new and useful improvements in bottle seals and has for its primary object to provide a frangible bottle seal interlockingly engaged with the bottle neck and overlying the usual closure cork to prevent tampering with the contents of the bottle and necessitating the destruction of the frangible seal to permit access to the closure cork for removal thereof.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a fragmentary vertical sectional view showing the bottle and neck with the frangible seal interlockingly engaged with the neck and overlying the closure cork;

Figure 2 is a fragmentary side elevational view with the seal removed and showing the recess in one side of the bottle neck for one leg of the locking key;

Figure 3 is a side elevational view of the seal;

Figure 4 is a perspective view of the seal locking key;

Figure 5 is a horizontal sectional view taken on line 5—5 of Figure 1;

Figure 6 is a horizontal sectional view taken on line 6—6 of Figure 1, showing the locking key engaged with the bottle neck and seal;

Figure 7 is a fragmentary vertical sectional view of another form of the invention showing a centering lug and slot on the bottle neck and seal;

Figure 8 is a fragmentary side elevational view showing the centering lug on the bottle neck;

Figure 9 is a horizontal sectional view taken on line 9—9 of Figure 7;

Figure 10 is a vertical sectional view of the seal showing the pocket in one side thereof to receive one leg of the locking key;

Figure 11 is a vertical sectional view of the seal showing the other side with the centering groove for the neck lug; and

Figure 12 is a horizontal sectional view of the seal.

Referring more in detail to the accompanying drawings, and particularly to Figures 1 to 6, there is shown a bottle seal for the bottle 55 1 that has a cylindrical neck 2 that receives the closure cork 3. One side of the bottle neck 2 is provided with an indentation or recess 4 defining upper and lower shoulders 5, while an angular groove 6 is formed in the bottle neck 60 2 above the recess 4.

The seal 7 of cap-shape as shown in Figures 1 to 3 may be constructed of any suitable frangible material, such as glass or the like, and when received on the bottle neck 2 rests 65 upon the bottle shoulder 8 as shown in Figure 1, the cap seal 7 being flared outwardly at its open end as at 9 and provided with an inwardly directed annular shoulder 10 substantially contacting the bottle neck. A locking 70 key in the form of a spring of inverted V-shape comprising legs 11 and 12 has the leg 11 positioned in the neck recess 4 with the upper and lower ends thereof in engagement with the recess shoulder 5, the locking key snugly 75 fitting within the recess and being retained against movement therein. With the locking key so disposed, and the closure cork 3 in the bottle neck, the cap seal 7 is then placed in position, the shoulder thereof engaging the 80 key leg 12 for moving the same inwardly toward the bottle neck with the free end of the spring leg 12 moving outwardly into engagement with the seal shoulder 10 when the seal is completely received on the bottle neck, 85 the locking key holding the seal in position.

To remove the closure cork 3 from the bottle neck, it is necessary to break or destroy the cap seal 7 and to facilitate this action, the seal 7 has a plurality of openings 13 arranged in a circumferential line registering with the annular neck groove 6. A suitable instrument, such as a nail N illustrated by dotted lines in Figure 1 is inserted through any one of the openings 13 in the seal and projected into the neck groove 6 to procure suitable leverage so that upon pivotal movement of the instrument N with the neck groove 6 as a bearing, the cap seal 7 is broken, and at 100

which time, the closure cork 3 may be easily removed.

In the form of the invention shown in Figures 7 to 12, the bottle 1^a has the neck 2^a receiving the closure cork 3^a, while one side of the bottle neck 2^a is provided with a recess 4^a having top and bottom shoulders 5^a, the upper end of the bottle neck 2^a being provided with an annular groove 6^a.

The cap seal 7^a when in seated position rests upon the shoulder 8^b of the bottle 1^a and is flared outwardly as at 9^a at its open end. The inner face of the cap seal 7^a is provided with a tapering recess 14 defining a lower shoulder 15, the recess 14 registering with the recess 4^a. Diametrically opposite the recess 4^a in the bottle neck 2^a, there is formed a triangular lug 16 of the form shown more clearly in Figure 8 that is adapted to be received in the triangular shaped recess 17 formed in the inner face of the cap seal 7^a diametrically opposite the recess 14. A locking key comprising the legs 11 and 12 is positioned in the registering recesses 4^a and 14, it being understood that the locking keys is first positioned in the recess 4^a before the cap is mounted upon the bottle while the cooperating lug 16 and recess 17 center or locate the recess 14 for the reception of the leg 12 of the locking key. The cap 7^a is provided with a circular series of openings 13^a registering with the annular groove 6^a for the reception of an instrument, such as nail N for breaking the cap seal 7^a to permit removal of the closure cork 3^a.

From the above detailed description of both forms of the invention, it is believed that the construction and operation thereof will at once be apparent, and while there are herein shown and described the preferred embodiments of the invention, it is nevertheless to be understood that minor changes may be made therein without departing from the spirit and scope of the invention as claimed.

43 I claim:

1. A device of the class described comprising a bottle having a neck with a recess therein and an annular groove above the recess, a frangible cap seal having an annular shoulder at its lower end, and a spring key of inverted V-form having one leg set into the neck recess and the other leg engaged with the cap seal shoulder, and said frangible cap seal having a circular series of openings alined with the neck groove for the insertion of an implement to facilitate breaking of the seal and removal of the bottle cork.

2. A device of the class described comprising a bottle having a neck with a recess therein and an annular groove above the recess, a frangible cap seal having a recess therein registering with the neck recess, and a co-operating centering lug and recess on the neck and cap, and said frangible cap seal having a circular series of openings alined

with the neck groove for the insertion of an implement to facilitate breaking of the seal and removal of the bottle cork.

3. A device of the class described comprising a bottle having a neck with a recess therein and an annular groove above the recess, a frangible cap seal having a recess therein registering with the neck recess, a lug on the bottle neck diametrically opposite the neck recess and a second recess in the cap for receiving the lug and disposed diametrically opposite the aforesaid cap seal recess, and said frangible cap seal having a circular series of openings alined with the neck groove for the insertion of an implement to facilitate breaking of the seal and removal of the bottle cork.

In testimony whereof I affix my signature.

PAUL SUSOL.
